SEWING MACHINE ATTACHMENT

Harold H. Pelzer, New York, N. Y., assignor to
Michael M. Scharf, New York, N. Y.

Application January 12, 1942, Serial No. 426,504

9 Claims. (Cl. 112—104)

This invention relates to attachments for sewing machines and more particularly to mechanism for feeding umbrella rib tips to a sewing machine for attaching said tips to an umbrella cover prior to mounting the cover upon the umbrella frame. Most rib tips are substantially cylindrical colored bodies about five-eighths of an inch long and have a through central opening for the attaching thread.

For convenience of illustration, reference is made to certain patents of Michael M. Scharf, particularly the apparatus shown in Patent No. 1,994,406 and his method Patent No. 1,798,110. In both of these patents there is shown a small tip holding or supporting pin, that is, the pin 73 in Fig. 2 of the first patent and the pin 10 in Fig. 1 of the second patent. Heretofore it has been necessary to place this small ornamental colored rib tip upon such pins by hand before the umbrella cover was stitched thereto, and the present invention is directed more particularly to a feeding mechanism for delivering the tips mechanically on to said pins whereby it is only necessary for the operator to place the fabric of the cover about the cylindrical portion of the tip and then start the sewing machine to stitch the cover thereto. While the invention will be hereinafter described with relation to its application to the Scharf style of sewing machine, it is however apparent to those skilled in the art that the feeding mechanism is equally applicable to the pins of other sewing machines for accomplishing the same purpose.

Accordingly, it is one of the objects of the present invention to provide a simple and practical tip feeding mechanism which will be reliable and efficient in use and operation.

A further object is to provide a compact self-contained mechanism which may be mounted upon a sewing machine now in use without material modification for quickly feeding the tips to the needle sewing position thereof.

A further object is to provide a time saving mechanism of the above general character which may be inexpensively manufactured and assembled.

A further object is to provide a mechanism of the character herein described which will be rapid in its operation and so constructed and arranged as to deliver easily and quickly the tips to the supporting pin with the thread receiving recess or perforation in line to receive the needle without breakage of either.

A further object is to insure that the tips in the feed mechanism are always in the correct

relative position for feeding to the sewing machine receiving pin.

A further object is to provide mechanism which may be actuated either by hand or by the knee of the operator as desired.

A further object is to provide a magazine which can be quickly removed with its full load of tips to be replaced by a duplicate magazine loaded with tips of a different color.

Other objects will be in part obvious and in part hereinafter pointed out in connection with the following analysis of this invention wherein is shown one of the various possible modifications and two alternative mechanisms for eliminating those tips which are not correctly positioned relative to the pin prior to their delivery to the pin.

In the accompanying drawings wherein similar reference characters denote corresponding parts throughout the several views,

Fig. 1 is a plan view showing the essential parts of the mechanism with certain parts of the machine table broken away in order to more clearly illustrate the relative positions of such parts.

Fig. 2 is an elevational view, partly in section, of a part of the feed mechanism.

Fig. 3 is an elevational view, partly in section, taken substantially on a line 3—3 of Fig. 1.

Fig. 4 is a detailed sectional view taken substantially on the line 4—4 of Fig. 3.

Fig. 5 is a partial sectional elevational view showing the hopper and magazine.

Fig. 6 is an enlarged detail sectional view of part of the mechanism shown in Fig. 5.

Fig. 7 is a detail view taken at right angles to Fig. 6 and substantially on the line 7—7 of Fig. 6.

Figs. 8 to 11, inclusive, are semi-diagrammatical detail elevational views, partly in section, showing the successive steps of feeding a tip to the holding pin.

Figs. 12 and 13 are similar views showing one of the means of discarding pins which are improperly delivered to the feed mechanism.

Fig. 14 is a detail sectional view taken substantially on the line 14—14 of Fig. 9.

Fig. 15 is an elevational view taken substantially on the line 15—15 of Fig. 3.

Fig. 16 is a detail sectional view taken on the line 16—16 of Fig. 15.

Figs. 17 and 18 are elevational views of the complete machine taken substantially at right angles to each other.

Fig. 19 is a plan view of important parts of

the mechanism and illustrates another form of discarding mechanism.

Fig. 20 is a partial sectional view taken substantially at right angles to Fig. 19, illustrating more particularly the discarding mechanism and a modified form of drive for the hopper and discarding mechanism.

Fig. 21 is a detailed elevational view partly in section showing the relative position of the modified form of discarding mechanism, the hopper feed, and magazine.

Figs. 22 to 26, inclusive, are detail views showing the various stages of operation of the modified form of discarding mechanism shown in Fig. 21.

Figs. 27 and 28 are detail views at right angles showing a detachable form of the magazine for quickly changing from one color tip to another.

Figs. 29 and 30 are detail views taken at right angles with the parts of the magazine in separated position.

Before starting upon a detailed description of the present invention, reference is first made to the general elevational views in Figs. 17 and 18, wherein is illustrated at right angles a conventional form of sewing machine head H mounted upon a suitable main table or base support 9 which carries the usual complementary stitch forming mechanism protected by a work table or support T thereabove. This form of sewing machine comprises the usual reciprocating needle 59 adapted to cooperate with a bobbin and looper beneath the work table T and at the left of the reciprocating needle 59 shown in Fig. 17 is pivotally mounted a pin 60 which corresponds to the pin 10 in Fig. 1 of Scharf Patent 1,798,110, or the pin 73 in his Patent 1,994,406. It is unnecessary to show further details regarding this pin and its relation to the sewing machine for they are well described in these patents. The pin 60 coacts with or enters the axial cylindrical opening in one end of the ornamental tip 11, clearly shown in Fig. 1. It will be noted that this umbrella tip is provided also with thread engaging means here shown as a transverse hole 36 slightly nearer to one end of the tip than the other for reasons hereinafter explained. This hole 36 during delivery is first adapted to be engaged by a carrier arm 64 and then moved laterally and slipped over the pin 60, as shown in Fig. 3, whereupon the arm 64 swings upwardly and moves to the right, thereby leaving the tip 11 free to be engaged by the needle 59, which carries the thread through the hole 36 in the tip in operative relation to the looper beneath the work table T prior to making the next stitch to one side after the other of the tip, as fully described in the method patent to M. M. Scharf, above noted.

Heretofore this positioning operation had to be done by hand, that is, the operator selected one of the ornamental tips from a receptacle of any sort and positioned the same manually upon the pin 60 with great care to assure that the hole 36 extending transversely through the tip 11 was vertically disposed and in registry with the path of travel of the needle 59. If, for example, the hole 36 in the tip shown in Fig. 3 where at an angle to the path of reciprocation of the needle, then the needle or tip would break as the needle impacted the tip, probably necessitating a replacement of the needle and rethreading of the machine with material loss of time. The present machine operates in a manner as will be hereinafter described and the operator knows

that the tip is properly placed upon the pin 60 with the transverse hole 36 in registry with the path of travel of the needle.

Referring now to the general positioning and arrangement of parts, attention is directed particularly to Figs. 1, 3 and 5, wherein is shown a hopper 10 of any convenient size and material adapted to contain a plurality of ornamental rib tips 11. This hopper has a chute 13 (Fig. 5) of a width and thickness adapted to permit a natural free horizontal feeding by gravity of the tips 11 which are constantly stirred or agitated by means of a beveled reciprocating plunger 14 passing over an opening 16 located in the front face 15 of the hopper 10 to the chute 13. This plunger 14 is mounted in a suitable guide (Fig. 5) and is reciprocated by means of a link 17 pivotally connected at its upper end to the plunger 14 by means of the pin 18 and pivoted at its lower end on a pin 19 eccentrically mounted upon a disk 20 driven by the shaft 21 mounted in suitable supporting bracket 22 on the base 9 of the machine, as shown in Fig. 3.

It will be noted that a gear 23 (Fig. 3) of the worm type meshes with a pinion 24 keyed to a drive shaft 25, which in turn carries a larger gear 26 meshing with a smaller pinion or gear 27 on shaft 28, which may be considered the main driving shaft for the various mechanisms herein shown. The purpose of this reduction gearing is to insure a relatively slow reciprocation of the agitator plunger 14 within the hopper 10, thereby tending to prevent breakage of the tips or tossing them out of the receptacle, as might otherwise occur if violent agitation took place.

The hopper 10 is provided with a movable lower bottom door 29, as shown in Fig. 5, normally urged to closed position as by any suitable means such as well-known spring hinges, the purpose being to permit a quick discharge or removal of the majority of these tips when desired, for it frequently happens one wishes to change the color of the tips to agree with the color of the cover used on the umbrella, and by such a construction a change of the tips may be accomplished very quickly, especially when taken in connection with the interchangeable magazines hereinafter described with relation to Figs. 27 to 30.

As the tips 11 are fed to the chute 13, it will of course be obvious that under normal circumstances approximately 50% will point in one direction and the other 50% in the opposite direction. Therefore it is necessary that some means be provided for insuring that these tips, when they reach the pin 60 (Fig. 3), for example, they will be in the correct position to be mounted thereon. This may be done in several different ways, only two of which will be herein illustrated and described.

At the lower end of the chute 13 is a revolving drum or magazine mounted in an outer shell 12 having a base secured as by means of screws 8 to the table 9, as shown in Figs. 1, 3 and 5. This shell 12 has centrally disposed therein a supporting shaft 31 upon which is mounted a magazine 30 having a circumferential series of separated ribs 30a, as shown in Fig. 6, spaced from each other a distance slightly in excess of the diameter of the tips 11. Thus, as these tips are fed down the chute 13 they will be received, one after another, in the recesses 32 and be carried in a clockwise direction about the central stud 31 as the magazine is rotated.

Between each pair of these separating members 30a is mounted a support 33 having an opening adapted to be pierced by a pin 35 surrounded by a coil spring 35a reacting between a collar carried by an enlarged axial extension 34 of pin 35 and an inner band of the magazine as shown at the left of Fig. 6. This extension 34 is provided with a cam head 39 which, as the magazine revolves in a clockwise direction, engages the tapered or bevelled edge of a cam 38 to be retracted into the central position shown in Fig. 6. Thus, with the parts in retracted position, the tip 11 designated at A in Fig. 6 will be free to rotate about its axis and the inner surface 37 of the outer casing 12 will rotate the tip as the wheel or magazine 30 rotates, thus bringing the transverse opening 36 into position to be engaged by the pin 35 when released from the cam and, when in such position, the spring 35a will force the pin 35 through the opening, thus holding the tip in that position throughout the rest of its travel about the drum or approximately through the remaining three hundred degrees of arc.

When the tip reaches the position shown at the top of its cycle, as in Figs. 5 and 8, it is then ready to be engaged by the feeder arm 64 and carried out of the magazine and on to the supporting pin 60.

This transfer mechanism is better shown in Figs. 8 to 11, inclusive, wherein is shown the pin 60, the reciprocating needle 59 and the upper part only of the rotatable magazine. The sides of the magazine are cut away to permit a pusher bar or rod 66 to pass completely therethrough, as shown in Figs. 3 and 8. This rod 66 is pivotally mounted at the upper end of a lever 51, which lever is in turn mounted upon a stud 57 carried by bracket 58, the lower end of which lever extends below the work table 9 and is adapted to be actuated by the knee of an operator against the action of a return spring 51a, as shown in Figs. 17 and 18.

Fig. 17 shows these parts in actuated position and, when pressure upon the lower end of the arm 51 is released, then the upper part of lever 51, as shown in Fig. 3, moves towards the right to retract the rod 66 entirely from the rotating portion of the magazine. The pusher rod 66 is connected with bar 61, which rides in a suitable slide bearing 63 and has pivotally mounted between its forward end and the end of a pusher rod 68 an arm 69 that supports the tip carrier 64. As shown in Fig. 8, the bar 61 is at its furthest position or at a point where the lever 51 has been moved to its extreme right or neutral position. Referring to Fig. 3, it will be noted that after this lever 51 is actuated to the position shown, a segmental rack 56 carried thereby, meshing with a pinion 55 secured on the shaft 48 mounted in the bearing block 58a, causes a rotation of the disk 49 in a clockwise direction to the position as shown. Further movement of the lever 51 and disc 49 is prevented by the stop pin P carried by the bearing block 58a contacting the pin 49a mounted on the periphery of the disc 49. The counterclockwise movement of the disc 49 and the return of lever to its inoperative or normal position is limited by the pin 49b also mounted on the periphery of disc 49 when it contacts stop pin P on the other side. This same movement may be accomplished by hand if the operator grasps a knob 50 and moves it in a clockwise direction a sufficient distance to accomplish the same result as to position in Fig. 3.

As the lever 51 moved in the position shown in

Fig. 10 it will have caused one of the ornamental tips 11 to be carried out of the magazine by reason of the split end of the carrier pin 64 riding down the surface of the cam block 65 to engage the hole 36 in the tip as illustrated in Fig. 9. This downward swing of the carrier pin 64 occurs when the lever 51 has moved toward the left only a very small distance and is caused to swing downward by means of the spring 69a, most clearly shown in Figs. 6 and 7, engaging the arm 69 to which is secured the carrier pin 64. The upper end of the arm 69 is connected to the end of the pusher rod 68 in such a manner to allow the arm to swing about its pivot as shown in Figs. 8 and 9 which illustrate this movement. Just as the end of the carrier pin 64 has completely entered the hole 36 of the tip, the forward end of the pusher rod 66 has contacted the rounded head of the tip (Fig. 9), and from this point the two pusher rods 66 and 68 move forward together, pushing the tip out of the magazine, the tip being held between the ends of the carrier pin 64 and the pusher rod 66. As the lever 51 nears the end of its movement, the tip 11 is pushed upon the split end of the pin 60 as illustrated in Fig. 10. At this point the shoulder 71 located at the right hand end of the pusher rod 68 contacts the stop pin 72, thereby preventing any further forward movement of the pusher rod 68. As the lever 51 continues to move to complete the rest of its movement which is very slight at this time, the bar 61, upon the end of which the arm 69 is pivoted continues to move forward.

This action causes the upper end of the arm 69 to act as the pivot point instead of its lower end and the resultant action causes the end of the carrier pin 64 to be withdrawn from the tip as shown in Fig. 11. When the pusher rod 68 is stopped by the pin 72 and the lever 51 must continue to move forward, their points of connection must change and this is accomplished, as most clearly shown in Fig. 14, by means of the arm 70 pivotally connected to the pusher rod 68 at one end and having its other end pinned to the stud 62 which is free to slide in a slot in the lever 51. The stud is rotatively mounted in the end of the bar 61 and also has secured to it the arm 66b pivotally connected to the block 66a which slidably engages the pusher rod 66 by means of well known pin and slot connection. It is easily seen that as the lever 51 continues to move forward carrying the bar 61 with it, the arm 70 will be turned in a clockwise direction as shown in Fig. 11. This turning action of the arm 70 also causes the block 66a to move forward compressing the spring which normally holds the push rod 66 in its extended forward position until the ring 73 secured on the rod contacts the side of the magazine 12. As the block 66a continues to compress the spring 67, the pin 75 carried by block 66a engages the hooked end of the flat spring 74 secured to the ring 73 to hold the push rods 66 and 68 in the position shown in Fig. 11.

When the lever 51 starts to return to the position shown in Fig. 8 the flat spring 74 continues to hold the push rods in the locked position which causes the carrier pin 64 to remain in raised position to prevent it from stripping the delivered tip off the pin 60. As the parts near the position shown in Fig. 8, the shoulder 71a of the push rod 68 contacts the stop pin 72. The continued movement of the lever 51 causes the stopped push rod 68 to pull the block 66a backward because of their being connected as already described. This backward movement of the block 66a brings

the turned down end of the flat spring 74 into contact with a releasing screw 76, carried on the lever 51, which forces the end of the flat spring downward away from the pin 75 thereby releasing the push rod 66 to allow the coil spring 67 to move it forward to its normal position.

When the push rod 68 was stopped by the pin 72 this allowed the bar 61 to release the carrier pin arm 69 but since the carrier pin 64 has been brought back into position over the bevelled block 65 it cannot swing downward into the magazine and comes to rest on said bevelled block 65, as shown in Fig. 8.

If, for any reason, a tip 11 is incorrectly positioned in the magazine, that is as illustrated in Fig. 12 for example, then the transverse hole 36 which is slightly longitudinally off center is not in a position to be engaged by the spring pressed carrier pin 64 as illustrated in Fig. 9. Consequently, as illustrated in Fig. 12, as the pusher rods 66 and 68 move towards the left, the carrier pin 64 moves downwardly off the bevelled block 65, missing the transverse hole 36 in the tip 11, and as the forward movement of the pusher rod 66 is continued and the tip is free of the magazine, the carrier pin 64 snaps downward, as shown in Fig. 13, to discharge the tip through an opening in the work supporting table of the sewing machine as illustrated.

This discharge of an incorrectly positioned tip must be accomplished by a full movement of the lever 51 in order to reset the carrier pin 64 as already described. After an incorrectly positioned tip within the magazine has been discharged, the magazine has been turned one position by the pawl 41 and the operator merely has to actuate the lever 51 again to feed another tip out of the magazine toward the pin 60.

The pawl 41 is pivotally mounted on the bell crank 43 by means of the screw stud 42 and is held in contact with the ratchet disc 40 by the spring 53 (Fig. 1). The bell crank 43 is supported on the stud 44 which is secured in an extension of the bearing block 58a (Figs. 1 and 2). The arm 45 of the bell crank 43 carries the roller 46 which contacts the hub of the disc 49 and is held in this position by means of the tension spring 54.

Carried on the hub of the disc 49 is the cam 47 which actuates the bell crank 43 upon the return of lever 51 to its inoperative position. The throw of the cam 47 is such that the pawl 41 will be moved upward the distance of one tooth of the ratchet disc 40 as shown in dot and dash lines of Fig. 3. This movement of the ratchet disc 40 in turn rotates the magazine 30 one position to bring another tip 11 into position. The spring pressed pawl 52 also engages the teeth of the ratchet disc 40 to insure perfect registration of the magazine 30.

Another form of mechanism for discarding tips prior to reaching the magazine is shown in Figs. 19 to 26, inclusive. This mechanism is directly associated with the feed chute 13 and includes a pusher rod 90 actuated by means of lever 87 mounted upon shaft 51, as in Figs. 20 and 21. The reciprocation of this pusher rod 90 is accomplished by means of a connecting link 86, the opposite end of which is eccentrically connected with a disk upon shaft 83 and driven by any suitable form of flexible gearing, such as spring belt 81, passing about a pulley 80 upon the shaft 28 and the idler pulley 80a which is free to rotate on the looper shaft of the sewing machine.

Thus, at regular intervals, the pusher rod 90, having a split end or pin 97, passes through an opening 91 in the side wall of the chute 13. The pusher rod slides in a suitable tubular guide 89 slidably mounted in the guide block 96 under the action of the lever 87. As this lever 87 moves towards the left, as shown in Fig. 20, its split pin or end 97 passes through the opening 91 in the chute 13 and if a tip is correctly positioned, as shown in Fig. 24, then the movement of the pusher arm 90 is arrested by reason of the engagement of the rounded head of the tip by the split pin end 97, and the surrounding spring 95 is compressed.

However, if the tip is incorrectly positioned, as shown in Fig. 20, then this split pin end 97 of the pusher rod 90 will pass through the opening 91 and engage the recess 92 in the end of the tip pointed in that direction and, as the pusher rod 90 moves toward the right, the tip will be drawn out of the chute, as shown in Figs. 22 and 25. When the tip is in this position, its shoulder at its head end is engaged by means of spring pressed stripper fingers 93 (Fig. 25) and pulled off of the supporting split pin 97, and drops into a suitable chute or receptacle 94 for discard.

It will be noted that the stripper fingers 93 are free to move inwardly and outwardly as the pusher rod 90 reciprocates. A sleeve 98 surrounds the spring 95 to prevent engagement between the stripper fingers and spring when the pusher rod moves toward the magazine, and the stripper fingers 93 remain in this position until the pusher rod is withdrawn, whereupon they coact with the ornamental collar about the head of the tip to assure its removal and discard. Since this pusher rod 90 with its split pin end 97 is reciprocating continuously, it contacts the end of each tip a number of times before the tip passes onward toward the magazine. This continuous feeding action for wrongly positioned tips in the chute 13 is provided to insure a steady supply of correctly positioned tips to the magazine should two or more wrongly positioned tips have to be discarded consecutively.

As previously stated, it is frequently desired to change the color of the tips fed to the sewing machine. It has already been explained how they may be quickly removed from the hopper by means of the door 29 (Fig. 5). This however does not eliminate the necessity of the operator having manually to eject the remaining tips in the magazine and the chute 13 and it is to eliminate all this loss of time that I devised the detachable magazine illustrated in Figs. 27 to 30. In Figs. 27, 28 and 29, for example, the supporting plate 99 carrying the shaft 31a and feed ratchet 40 and its operating parts is permanently secured to the bed or base of the machine above the work table 9. The tip feed and ejector mechanism remains exactly as already described, and it is only necessary to actuate a release mechanism such as a spring catch 100 passing through an opening 101 at the base of the removable support portion 102 of the magazine, whereupon the magazine 30, including its housing 103, support 102 and all of the tips carried thereby, may be removed bodily from the shaft, as shown in Fig. 29, and a substitute magazine is placed upon the shaft 31a, in accordance with the arrangement in Fig. 27. The magazine otherwise is of similar construction to that illustrated in Figs. 3 and 5, the main difference being that it receives its turning motion by means of a clutch 104.

The operation of this machine is clear from

the above description. It is sufficient to state that when the sewing machine is ready for operation the usual clutch is thrown in and then the continuously running power shaft 23 will drive the other parts first to continuously agitate the tips within the hopper, as shown in Fig. 5. Actuation of the lever 51 manually will cause a rotation of the magazine, and likewise an operation of the tip feeding mechanism shown in Fig. 3 to carry the tip from the magazine over to the pin 60 as shown in Figs. 8 to 11, inclusive. If, for any reason, a tip is improperly positioned within the magazine, then it will be automatically discharged by the mechanism shown in Figs. 12 and 13. If this form of discarding mechanism is replaced, then the incorrectly positioned tips may be removed by the mechanism shown in Figs. 19 to 26, inclusive, for example.

When it is desired to change the color of the tips another magazine is easily and quickly substituted by means of the mechanism and arrangement of parts shown in Figs. 27 to 30, inclusive.

It will thus be seen that the present invention comprehends a reliable and efficient mechanism which may be inexpensively manufactured and quickly applied to machines now in use, thereby greatly speeding up the operation of such machines and eliminating the personal element in applying ornamental umbrella tips to the support on a sewing machine while the same are being secured to the fabric forming the umbrella cover.

Definite assurance is provided for feeding the tips not only in the correct relative position to the support at all times and discard those which are improperly positioned, but to be assured that the attaching hole in the tip is in registry with the line of travel of the needle to prevent breakage of any of the parts and particularly the needle. In short, the invention is adapted to accomplish among others, all of the objects and advantages herein set forth.

I claim:

1. A sewing machine for sewing umbrella tips having axial recesses at corresponding ends and thread receiving means between the opposed ends, to umbrella covers, including a reciprocable needle, a pin engageable within a tip recess for supporting said tip with its thread receiving means in alignment with said needle, reciprocable means movable substantially axially of said pin for moving tips into position on said pin and means for positioning successive tips in the path of movement of said last mentioned means.

2. A mechanism as set forth in claim 1, including a tip container, an agitator therein, a chute leading therefrom, a magazine, and means for ejecting the tips from the chute which are improperly positioned therein to subsequently coat with the pin for registry of the thread receiving means with the needle.

3. A mechanism as set forth in claim 1, including a tip container, an agitator therein, a chute leading therefrom, a magazine, and mechanism including a reciprocating rod for ejecting

the tips from the chute which are improperly positioned therein to subsequently coat with the pin for registry of the thread receiving means with the needle.

5. A mechanism as set forth in claim 1, including a tip container, an agitator therein, a chute leading therefrom, a magazine, means for ejecting the tips from the chute which are improperly positioned therein to subsequently coat with the needle, and means for rotating the magazine after each tip has been sewn to the cover to bring another tip in position to be delivered to the pin.

10 5. In combination with a sewing machine for sewing umbrella tips having axial recesses at corresponding ends and thread receiving means between the opposite ends, to umbrella covers, a needle, a pin adjacent said needle, adapted to engage said axial recesses when said tips are delivered in one position, means for delivering said tips in said one or a reverse position, means for selecting only those tips in said one position for delivery to said sewing machine and depositing only said last mentioned tips on said pin in sewing position with each thread receiving means in perfect alignment to receive said needle without breakage to either said tip or said needle.

15 6. A sewing machine for sewing umbrella tips having axial recesses at corresponding ends and thread receiving means between the opposed ends to a cover, comprising a reciprocable needle, a pin engageable within a tip recess for supporting the tip with its thread receiving means aligned with the needle, a receptacle for receiving a plurality of tips, a revolvable tip magazine, means for delivering tips in succession from said receptacle to said magazine, means in said magazine for positioning the tips for alignment of said thread receiving means with the needle, movable means operative to deliver tips having their recessed ends toward said pin from said magazine into engagement with the pin in sewing position, said last means being operative upon tips having their recessed ends oppositely disposed to eject same from said magazine without delivery to the pin.

20 45 7. A mechanism as set forth in claim 6, together with means for rotating the magazine alternately with the operative movement of the ejecting means, said ejecting means including a reciprocating rod and a carrier pin, said rod and pin coating with the tip in the reciprocation of the rod to either eject the same or to place the tip in position to be stitched by the needle depending upon the part of the tip engaged by said rod.

25 55 8. A mechanism as set forth in claim 6 together with means for rotating the magazine alternately with the operative movement of the ejecting means.

30 9. A mechanism as set forth in claim 1, including means for discarding tips improperly positioned by the positioning means for reception of the pin in the recesses and alignment of the thread receiving means with the needle.
